WILLIAM E. WILLIAMS
BY *Arthur L. Sles* ATTY.

UNITED STATES PATENT OFFICE.

WILLIAM E. WILLIAMS, OF SAN FRANCISCO, CALIFORNIA, ASSIGNOR OF ONE-HALF
TO MAURICE A. LYONS, OF SAN FRANCISCO, CALIFORNIA.

ELECTRIC CONTACT.

Application filed April 4, 1923. Serial No. 629,925.

To all whom it may concern:

Be it known that I, WILLIAM E. WILLIAMS, a citizen of the United States, residing in the city and county of San Francisco and State of California, have invented a new and useful Improvement in an Electric Contact, of which the following is a specification.

My invention relates to improvements in electric contacts arranged to be actuated by the opening of a door to close an electric circuit, to a buzzer or other alarm.

The primary object of my invention is to provide an improved contact for closing an electric circuit.

Another object is to provide an improved device which may be detachably mounted upon the hinge of a door to cooperate therewith to close an electric circuit when the door is in a partially open position.

A further object of my invention is to provide a device adapted to facilitate installation and to occupy an extremely inconspicuous position.

A still further object is to provide a device of improved construction affording simplicity and effectiveness and which may be manufactured at an extremely low cost.

I accomplish these and other objects by means of the device disclosed in the drawings forming a part of the present specification wherein like characters of reference are used to designate similar parts throughout said specification and drawings and in which,

Fig. 1 is a vertical section of a portion of a door casement showing a portion of a hinge and my improved contact as applied therein.

Fig. 2 is a horizontal section of a plan view of the hinge and contact.

Fig. 3 is a broken vertical section taken upon the line 3—3 of Fig. 2 in the direction indicated.

Fig. 4 is a side elevation of my improved contact.

Fig. 5 is a view showing the blank from which the grounding contact is shaped.

Fig. 6 is a view showing the manner in which the insulating material and the second contact are assembled upon the grounding contact.

My invention is primarily intended for

mounting in association with a hinge and door to close an electric connection to a buzzer, bell, or other signaling device intended to give notice that the door has been opened. Referring particularly to the drawings the numeral 1 is used to denote a door mounted within a casement 2 upon a hinge 3 consisting of a pair of butts 4 and 5 connected by means of the usual pintle 6. The hinge is commonly mounted with a portion of the butts and the pintle extending outwardly a slight distance from the door and casement to provide a clearance when the door is swung to an open position.

My improved contact consists of a pair of conductors 7 and 8 insulated from each other by means of a strip 9 of insulating material. The conductor 7, hereinafter termed the grounding contact, is formed from a strip of conductive metal, one end of which is doubled back in parallel relation to and slightly spaced from the body of the conductor to form a yoke adapted to fit over the upper edge of one of the butts of the hinge 3. The conductor 8 is formed from a slightly narrower strip of conductive metal, one end of the strip being shaped to provide a resilient spring contact finger 10 arranged to extend over the other butt of the hinge 3 and to be engaged thereby when the hinge is in a partially open position as hereinafter more fully described.

The insulating strip 9, which may be of any suitable insulating material, is made of a width slightly greater than the conductor 8, the edges of the strip 9 being folded around the edges of the strip 8. The conductor 8 and the insulating strip 9 are secured upon the conductor 7 by means of tabs 11 formed upon the edges of the conductor 7, said tabs being bent over and pressed against the folded edge of the insulating strip to hold the same firmly against the conductor 8.

The conductors 7 and 8 and the strip 9 are stamped from suitable sheet material and shaped as shown in the drawings. The shaped parts are then assembled by placing the insulating strip 1 between the conductors as shown in Fig. 6 of the drawings, the edges of the insulating material being folded over the edge of the conductor and the tabs 11 bent as shown in dotted lines.

Extensions 12 and 13 are outwardly bent upon the ends of the conductors 7 and 8 respectively and apertured to receive terminals 14 and 15 of an electric circuit.

5 The operation of the device is as follows. The grounding contact 7 is pressed over the upper edge of one of the butts of the hinge 3, and the terminals 14 and 15 of an electric circuit, connected in the well known manner through a suitable source of electrical energy to a buzzer or other alarm not shown, attached upon the extensions 12 and 13. When the door 1 is consequently the hinge 3, is in the closed position the contact finger 10 will extend across the other butt of the hinge in slightly spaced relation thereto. In practice the device is mounted upon the stationary butt 4 so that the terminals will remain in fixed position upon the back of the hinge. The placing of the conductor 7 upon the butt 4 causes the terminal 14 to be grounded upon the hinge. The conductor 8 is insulated from the conductor 7 so that while the finger 10 is held in spaced relation to the hinge, the circuit will be normally broken between the terminals 14 and 15. When now the door is opened the butt 5 of the hinge will be moved away from the stationary butt 4 and caused to engage the contact finger 10 as shown in dotted lines in Figs. 2 and 3 of the drawings, the finger 10 being so shaped that the outer end will be engaged and slightly lifted when the butt is moved thereunder. In this manner a connection will be effected between the conductor 8 and the hinge whereby the circuit will be closed through the hinge and the buzzer or other alarm caused to sound in the usual manner. As the door is further moved the hinge butt 5 will be moved past the finger 10 and the circuit thus be broken while the door is open. The outer end of the finger 10 is upwardly turned to permit the hinge to be moved thereunder when returned to the closed position.

From the above description it will be seen that I have provided a device which is of extremely simple construction and which may be readily attached upon the ordinary door hinge. It will be noted that no moving parts are required thereby insuring durability and permitting the device to be made at an extremely low cost. The contacts are relatively small and being fitted closely over the upper edge of the hinge are very inconspicuous. The connections 14 and 15 are easily attached, and being connected upon the back of the hinge may be readily concealed so as not to mar the appearance of the door. The precise arrangement and construction of the parts may of course be modified in many ways without departing from the spirit of my invention. I therefore do not wish to restrict myself closely to the disclosure made but desire to avail my-

self of such modifications as may fall within the scope of the appended claims.

Having thus described my invention what I claim as new and desire to secure by Letters Patent is—

1. An electric contact comprising a conductor adapted for detachable engagement with one outwardly extending butt portion of the hinge of a door; a second conductor secured in insulated relation to the first conductor, both of said conductors being arranged to receive terminals of an electric circuit; and an extension formed upon the second conductor arranged to normally extend past the opposite butt portion of the hinge and to engage the same momentarily to close a circuit when said hinge butt is moved therepast by the movement of the door. 75 80 85

2. An electric contact comprising a conductor adapted for detachable engagement with one outwardly extending butt portion of the hinge of a door and arranged to receive one terminal of an electric circuit for grounding the same upon the hinge; a second contact mounted upon the first conductor and insulated therefrom said second conductor being arranged to receive another terminal of the electric circuit, said circuit being broken between said conductors; and a spring finger formed upon the second conductor arranged to normally extend past the opposite butt portion of the hinge and to engage and form electrical connections with the hinge momentarily when the door is moved through a partially open position. 100

3. An electric contact comprising a conductor shaped to detachably engage the stationary butt of a hinge and arranged to receive one terminal of an electric circuit to ground the same upon said hinge; a second conductor having an extension arranged to receive the other terminal of the circuit, said second conductor being provided with a spring finger arranged to normally extend past the movable butt of the hinge and to momentarily engage said movable butt when moved thereunder; and a strip of insulating material secured between said conductors whereby a circuit is completed through said conductors only when both conductors engage the hinge. 105 110 115

4. An electric contact comprising a conductor stamped from sheet metal and shaped to engage one butt of a hinge, said conductor being arranged to receive one terminal of an electric circuit for grounding the same upon the hinge; a second contact arranged to receive another terminal of the circuit and provided with an extension arranged to engage the other butt of the hinge when said hinge is in a partially open position; a strip of insulating material mounted between said conductors to normally break the circuit between said conductors; and tabs formed 130

upon the first conductor and bent over the insulating material to secure the insulating material and the second conductor thereon.

5. An electric contact comprising a pair of conductors arranged to receive terminals of an electric circuit; a strip of insulating material mounted between said conductors and folded to partially enclose one of the conductors; tabs formed upon the other conductor and bent against the folded portion of the insulating material to secure said insulating material and the first conductor

upon the body of said other conductor; an extension formed upon one of the conductors to detachably engage in one butt of a hinge 15 to form a grounding connection therewith; and a spring finger formed upon the other conductor to engage the other butt and form an electric connection therethrough when the hinge is in a partially open position. 20

In witness whereof I hereunto set my signature.

WILLIAM E. WILLIAMS.
